NAIL POLISH APPLICATOR

William R. Perillo, New York, N. Y.

Application April 25, 1940, Serial No. 331,503

6 Claims. (Cl. 15—133)

This invention relates to new and useful improvements in devices for applying liquid nail polish to the finger nails of the human hands and this application is a continuation in part of my application for half moon automatic nail polish applicator, Serial Number 300,211, filed October 19, 1939.

It is the object of the present device to provide a device by means of which liquid nail polish may be applied to the nails of the human hands or toes in a neat and evenly distributed manner with the exercise of little effort upon the part of the user.

A feature of the invention resides in a novel construction whereby in the application of the polish, the so-called half moon at the base of the nail will be preserved as will also a portion of the outer free end edge of the nail.

Another feature of the invention resides in a novel construction whereby the device is guided with respect to the finger or toe nail when in use, thus insuring an even application of the polish.

A further feature of the invention resides in a novel construction whereby a complete application of nail polish to the desired area of the surface of the nail, may be had with a single stroke of the device.

Still a further feature of the invention resides in means for readily attaching and detaching the device to a bottle or similar container or receptacle for the nail polish.

In the accompanying drawing, I have illustrated a preferred embodiment of my invention, which however, is merely illustrative and is not to be considered as limiting the invention beyond the scope of the appended claims.

In the drawing:

Figure 1 is a perspective view illustrating the manner of use of a device constructed in accordance with the present invention.

Figure 2 is a fragmentary central longitudinal sectional view on an enlarged scale.

Figure 3 is a top plan view.

Figure 4 is a bottom plan view on an enlarged scale.

Figure 5 is a detail sectional view on an enlarged scale, and;

Figure 6 is a detail fragmentary view illustrating a detail of construction.

The device comprises a main body portion 10 of general tubular form and preferably, although not necessarily, of circular cross sectional form. This body portion 10 is constructed of relatively soft pliable material such as rubber, the walls of the body being of such thickness as to give stability to the body and yet permit of its partial collapse under pressure in order to effect a discharge of the contents thereof.

In use, the body portion 10 is adapted to be attached to a bottle or similar container or

receptacle 11 and to accomplish this end, a tubular coupling member such as 12 is employed.

The coupling member 12 is formed from hard rubber, metal or other suitable rigid material having one end tapered as at 13 for insertion into the mouth of the receptacle 11. The opposite end of the coupling member 12 is provided with a reduced portion 14 adapted for reception in the rear end 15 of the body portion 10 as illustrated in Figure 2 of the drawing. A vent opening 16 is provided in the coupling member 12 to permit of free flow of the fluid through the body portion 10 when the device is in use.

The opposite or outer end of the body portion 10 is flared outwardly as indicated at 17 in the drawing and terminates in an outer edge consisting of two angular side edges 18 which are connected by an intermediate curved edge 19.

The forward end of the body portion 10 is formed with a continuous discharge opening 20 of slit-like form which extends throughout the length of the two angular side edges 18 and the curved edge 19. The top wall 21 of the flared end of the body portion 10 has its forward edge projected slightly beyond the forward edge of the lower wall 22 thereof as indicated at 23 in Figure 5 of the drawing. This construction provides a lip-like overhanging portion above the discharge opening 20 and the discharge opening 20 is spaced slightly from the nail by the thickness of the material of the lower wall 22 when the device is in position for use.

By the construction just described, fluid discharged through the discharge opening 20 will be directed to the nail surface by the portion 23 of the upper wall which, however, does not contact the nail surface as is clearly shown in Figure 2 of the drawing.

Means is employed to spread the nail polish evenly over the surface of the nail. This means may be formed from felt, rubber or any suitable material. However, I prefer to employ a brush-like structure of relatively fine bristles. The brush-like structure consists of a thin line of bristles 24 which project outwardly and downwardly from the outer edge of the projected portion 23 of the top wall 21 of the body portion 10 and this line of bristles extends throughout the length of the angular side edges 18, the intermediate connecting curved edge 19 and the discharge opening 20.

The under face of the bottom wall 22 of the flared end of the body portion 10 is formed with a curved or concaved recess 28, the forward edge of which follows the contour of the angular side edges 18 and the intermediate curved connecting edge 19, the rear end of this recess terminating in a curved edge 29. This recess provides a clearance 30, see Figure 2, which permits of placing the device in operative position without

contact with the nail except by the forward edge of the lower wall 22 of the flared forward end of the body portion 10, as illustrated in Figure 2.

The device is used in the following manner: Having been attached to the container 11, it is grasped between the index finger and the thumb, is inverted and placed upon the nail to be treated, as illustrated in Figure 1 of the drawing.

It is to be understood that the device is to be made in a number of sizes in order that a size appropriate for use upon the nail to be treated may be selected.

When in position, the intermediate curved edge 19 will be spaced with respect to the base of the nail with the outer ends of the angular side edges 18 in contact with the cuticle of the finger at their respective sides of the nail. As illustrated in Figure 6 of the drawing, the angular side edges 18 are preferably formed with slight projections 40 which engage the cuticle to form a guiding means for the device as it is moved in operation.

With the device in position as above described, the body portion 10 is subjected to slight pressure to effect a discharge of polish from the discharge opening 20 directly upon the nail. The device is now moved towards the end of the finger whereupon the spreader, that is the bristles 24, spread the polish evenly over the surface of the nail.

By reference to Figure 1, it will be noted that by reason of the curvature of the edge portion 19, the so-called half moon portion of the nail designated 42 in said figure, will not receive the polish and will thus be preserved. If now the stroke is terminated before the outer end of the nail is reached, a portion at the outer end of the nail will likewise receive no polish as indicated at 43 in Figure 1, or if desired, the stroke may be carried to the end of the nail to cover completely the upper surface thereof.

From the foregoing, it will be apparent that the present invention provides a device by which the application of a polish to the nails of the fingers or toes of the human body may be carried out in a highly satisfactory manner.

Having thus described the invention, what is claimed as new, is:

1. A device of the character described comprising in combination, a tubular body, means for attaching one end of the tubular body to a bottle or similar receptacle, the opposite end of the tubular body terminating in a relatively thin outwardly flared portion having angular side edges connected by an intermediate curved end edge, a relatively narrow discharge opening extending throughout the length of the angular side edges and the curved connecting edge of the tubular body, and a concaved recess formed on the under side of the tubular body and extending rearwardly thereof from the curved end edge.

2. A device of the character described comprising in combination, a tubular body, means for attaching one end of the tubular body to a bottle or similar receptacle, the opposite end of the tubular body terminating in a relatively thin outwardly flared portion having angular side edges connected by an intermediate curved end edge, a relatively narrow discharge opening extending throughout the angular side edges and the curved connecting edge of the tubular body, a concave recess formed upon the under side of the tubular body and extending rearwardly

thereof from said curved edge, and a spreading element for trailing the discharge opening when the device is in operation.

3. A device of the character described comprising a tubular body of flexible material, means for attaching one end of the tubular body to a bottle or similar receptacle, the opposite end of the tubular body terminating in a relatively thin outwardly flared portion having angular side edges connected by an intermediate curved end edge with the outer edge of the upper wall of the flared portion extended to a point beyond the outer edge of the lower wall thereof, said upper and lower walls of the flared portion being slightly spaced to provide a discharge opening of slit-like form, and a spreading element carried by the projecting edge of the upper wall of the flared portion and extending angularly therefrom.

4. A device of the character described comprising a tubular body of flexible material, means for attaching one end of the tubular body to a bottle or similar receptacle, the opposite end of the tubular body terminating in a relatively thin outwardly flared portion having angular side edges connected by an intermediate curved end edge with the outer edge of the upper wall of the flared portion extended to a point beyond the outer edge of the lower wall thereof, said upper and lower walls of the flared portion being slightly spaced to provide a discharge opening of slit-like form extending throughout the length of the angular side edges and the curved connecting end edge, and a plurality of relatively fine bristles projecting outwardly and downwardly from the upper wall of the flared portion in position to trail the discharge opening during operation of the device.

5. A device of the character described comprising a tubular body of flexible material, means for attaching one end of the tubular body to a bottle or similar receptacle, the opposite end of the tubular body terminating in a relatively thin outwardly flared portion having angular side edges connected by an intermediate curved end edge with the outer edge of the upper wall of the flared portion extended to a point beyond the outer edge of the lower wall thereof, said upper and lower walls of the flared portion being slightly spaced to provide a discharge opening of slit-like form extending throughout the length of the angular side edges and the curved connecting end edge, a plurality of relatively fine bristles projecting outwardly and downwardly from the upper wall of the flared portion in position to trail the discharge opening during operation of the device, and a concaved finger nail receiving recess formed upon the under face of the lower wall of the flared portion.

6. A device of the character described comprising in combination, a tubular body, means for attaching one end of the tubular body to a bottle or similar receptacle, the opposite end of the tubular body terminating in a relatively thin outwardly flared portion having angular side edges connected by an intermediate curved end edge, a cuticle engaging projection extending from the outer end of each of the angular side edges, a discharge opening extending throughout the length of the angular side edges and the curved connecting edge of the tubular body, and a concaved recess formed on the under side of the tubular body and extending rearwardly thereof.
